UNITED STATES PATENT OFFICE.

EMIL C. NAGEL, OF CHICAGO, ILLINOIS.

ADJUSTABLE SOCKET-WRENCH.

No. 900,766.

Specification of Letters Patent.

Patented Oct. 13, 1908.

Application filed November 19, 1907. Serial No. 402,933.

To all whom it may concern:

Be it known that I, EMIL C. NAGEL, a citizen of the United States, residing at Chicago, in the county of Cook and State of Illinois, have invented new and useful Improvements in Adjustable Socket-Wrenches, of which the following is a specification.

My invention relates to improvements in an adjustable, socket wrench in which set-screws, nuts, bolt heads etc., of different sizes may be tightened or loosened up as the case may be; and the objects of my improvements are, first, to provide a suitable and durable socket wrench; second, to afford facilities for the proper adjustment of the reins to suit the various sizes of nuts, cap-screws, bolt head etc., as is met with in practice within the range of the wrench; third, to make the wrench compact as possible as wrenches of this class should be. I attain these objects by the mechanism illustrated in the accompanying drawing, in which:—

Figure 1. is a complete view of the wrench ready for use on large nuts, cap-screws etc. Fig. 2 is another view of the lower part of Fig. 1. showing the reins of the wrench closed and ready for use on smaller work than is shown in Fig. 1. Fig. 3. shows a plan or end view of the socket end of the wrench, illustrating the shape or form of the socket for hexagon nuts etc. Fig. 4. is a view of the open link removed from the reins of Fig. 1.

Similar figures refer to similar parts throughout the several views.

The wrench is to be drop, or machine forged from steel the principal forging consisting of the lower part of the wrench see Figs., 1, 2. 5 being the shank of the wrench while 7 are the reins. In Fig. 1. the reins are shown open this being the normal posi-

tion of the reins while in Fig. 2. the reins are shown closed, being held so by the reinforcing collar 12 and thumb screw 13. It will be observed that this set collar 12 serves the double purpose of reinforcing the reins 7, Fig. 2. when the wrench is used on small work, and also when the wrench is used on larger work this set collar 12 is slipped up the reins 7, to the position shown in Fig. 1. thereby reinforcing the reins at their apex. When the wrench is used on larger work an additional reinforcing link 10, (shown in detail Fig. 4.) with the opening 11, is slipped over the reins 7, below the collar 12 and seats itself in the corrugations 23. This open link 10 also does or serves the duty of reinforcing the reins 7.

Fig. 3. is a plan or an end view of the socket end of the wrench when the reins are in the position shown in Fig. 2. 8 represents the face or end of the socket while 9 shows the recessed socket.

I am aware that prior to my invention adjustable socket wrenches have been made with pivoted reins. I therefore do not claim such a combination broadly; but

I claim:

1. A wrench having spring jaws at its end provided with work engaging sockets combined with an open link and a reinforcing collar adapted to compress or lock said jaws as set forth.

2. A wrench having spring jaws at its end provided with work engaging sockets combined with an open link and a reinforcing collar with set screw therefor adapted to compress or lock said jaws as set forth.

EMIL C. NAGEL.
